UNITED STATES PATENT OFFICE.

HENRY LANGE, OF QUINCY, ILLINOIS.

DESIGN FOR A COAL RANGE.

Application filed July 19, 1927. Serial No. 22,808. Term of patent 14 years.

To all whom it may concern:

Be it known that I, HENRY LANGE, a citizen of the United States, residing at Quincy, in the county of Adams, and State of Illinois, have invented a new, original, ornamental Design for Coal Ranges, of which the following is a specification, reference being had to the accompanying drawing, forming part thereof.

The figure is a perspective view of a coal range, showing my new design.

I claim:

The ornamental design for a coal range, as shown.

HENRY LANGE.
